UNITED STATES PATENT OFFICE.

JOSEPH ALTSCHULER, OF LOS ANGELES, CALIFORNIA.

FILM-RACK.

1,369,873.

Specification of Letters Patent.

Patented Mar. 1, 1921.

Application filed May 7, 1919. Serial No. 295,505.

To all whom it may concern:

Be it known that I, JOSEPH ALTSCHULER, a citizen of the United States, residing at Los Angeles, in the county of Los Angeles and State of California, have invented a new and useful Film-Rack, of which the following is a specification.

My invention relates to the art of preparing and developing motion picture films.

10 The principal object of my invention is to provide a rack by means of which the process of developing and washing such films can be greatly facilitated. It is common practice in the art to provide a flat rack 15 around which the film is wound while it is being developed. The film, however, tends to change its condition when immersed in the various solutions, stretching and contracting so that it has a variable length and 20 there is danger of adjacent convolutions overlapping or touching with possible damage to the film.

One of the objects of my invention is to provide a film rack which will be so constructed that the film will be retained in a tight and uniform tension during the developing, washing and drying process.

Further objects and advantages will be evidenced hereinafter.

30 Referring to the drawings which are for illustrative purposes only,

Figure 1 is a perspective view of the film rack embodying my invention.

Fig. 2 is a section through said rack.

35 Fig. 3 is an enlarged section of one end of the rack.

The rack as illustrated has rigid side members 11 having central holes 12 therein upon which the rack may be rotated for winding, 40 and having braces 13 and fixed end members 14 securing the side members 11 rigidly together. Sliding in slots 20 formed in the side members 11 is a movable end member 21; this member having a cross section as 45 shown in Fig. 3 and being provided with pins 22 and spiral springs 23 at either end thereof as shown in Fig. 1. Wedges are provided for holding member 21 in its depressed position.

50 The method of operation of my invention is as follows:

The wedges 30 being put in place the spiral springs 23 are forced downwardly and the member 21 is held in its lower position.

55 The rack being mounted on a suitable bar passing through the holes 12, the film is

wound around the members 14 and 21 as shown in Fig. 1, the ends being secured by any suitable means not shown. The wedges 30 are then removed and the springs 23 exert 60 a pressure on the member 21, putting an even tension on the film. The film may now be placed in any sort of a developing bath in which it may expand to a considerable degree, this expansion being taken up by 65 springs 23; the film being then dried upon the rack, contracts, pulling the member 21 back into its original position. Whenever it is desired to unwind the film the wedges are replaced and the rack is again mounted 70 on the bar and the film unwound.

I claim as my invention:

1. A film rack comprising two rigid side members having central holes about the axis of which said rack may be rotated; a fixed 75 end member rigidly secured between said side members; cross braces secured between said side members; a movable end member sliding in slots in said side members; wedges for holding said movable end member in 80 its depressed position; a second fixed end member rigidly secured in said side members adjacent to said movable end member; and compression springs between said second fixed end member and said movable 85 end member.

2. A film rack comprising two rigid side members having central holes about the axis of which said rack may be rotated; a fixed 90 end member rigidly secured between said side members; cross braces secured between said side members; a movable end member sliding in slots in said side members; a second fixed end member rigidly secured in 95 said side members adjacent to said movable end member; and compression springs between said second fixed end member and said movable end member.

3. A film rack comprising two rigid side members having central holes about the axis 100 of which said rack may be rotated; a fixed end member rigidly secured between said side members; a movable end member sliding in slots in said side members; wedges for holding said movable end member in 105 its depressed position; a second fixed end member rigidly secured in said side members adjacent to said movable end member; and compression springs between said second fixed end member and said movable end 110 member.

4. A film rack comprising two rigid side

members having central holes about the axis of which said rack may be rotated; a fixed end member rigidly secured between said side members; a movable end member sliding in slots in said side members; a second fixed end member rigidly secured in said side members adjacent to said movable end member; and compression springs between said second fixed end member and said movable end member.

5. A film rack comprising two rigid side members having central holes about the axis of which said rack may be rotated; a fixed end member rigidly secured between said 15 side members; cross braces secured between said side members; a movable end member sliding in slots in said side members; wedges for holding said movable end member in its depressed position; and springs for forcing 20 said movable end member outwardly in said slots.

6. A film rack comprising two rigid side members having central holes about the axis of which said rack may be rotated; a fixed 25 end member rigidly secured between said side members; cross braces secured between said side members; a movable end member sliding in slots in said side members; and springs for forcing said movable end member outwardly in said slots.

7. A film rack comprising two rigid side members having central holes about the axis of which said rack may be rotated; a fixed end member rigidly secured between said

side members; a movable end member sliding in slots in said side members; wedges for holding said movable end member in its depressed position; and springs for forcing 35 said movable end member outwardly in said slots.

8. A film rack comprising two rigid side members having central holes about the axis of which said rack may be rotated; a fixed end member rigidly secured between said 40 side members; a movable end member sliding in slots in said side members; and springs for forcing said movable end member outwardly in said slots.

9. A film rack comprising two side bars and two fixed end bars, the side bars extending beyond one of the end bars and provided with slots, a bar movably supported in said slots, and yielding means between the movable bar and the adjacent fixed end bar for forcing the movable bar outwardly. 50

10. A film rack comprising two side bars and two fixed end bars, the side bars extending beyond one of the end bars and provided with slots, a bar movably supported in said slots and yielding means between the 60 movable bar and the adjacent fixed end bar for forcing the movable bar outwardly and means for locking the movable bar against outward movement.

In testimony whereof, I have hereunto set 65 my hand at Los Angeles, California, this 28th day of April 1919.

JOSEPH ALTSCHULER.
